DESIGN FOR A FIELD TELEPHONE

Camillo A. Knorr, East Orange, N. J., assignor to
Federal Telephone and Radio Corporation, New
York, N. Y., a corporation of Delaware

Application February 12, 1945, Serial No. 117,892

Term of patent 14 years

(Cl. D26—14)

Be it known that I, Camillo A. Knorr, a citizen of the United States, residing at 9 Church Place, East Orange, Essex County, State of New Jersey, have invented a new, original, and ornamental Design for Field Telephone, of which the following is a specification, reference being had to the accompanying drawings, forming part thereof.

Figure 1 is a perspective front view of the field telephone, showing my new design, the casing being opened up and the receiver removed;

Fig. 2 is a perspective front view of my design

shown in Fig. 1, the receiver being set on the field telephone, and

Fig. 3 shows a perspective front view of my design as shown in Fig. 1, the casing being in closed position.

The dominant features of my design reside in the portions shown in full lines.

I claim:

The ornamental design for a field telephone, as shown and described.

CAMILLO A. KNORR.
